UNITED STATES PATENT OFFICE.

GUSTAV EGLOFF AND HARRY P. BENNER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA.

APPARATUS FOR TREATING HYDROCARBONS.

Application filed July 15, 1920, Serial No. 396,471. Renewed August 14, 1926.

This invention relates to improvements in apparatus for treating hydrocarbons and refers more particularly to an apparatus adapted for the cracking of hydrocarbon oils.

5 The objects of the invention are to provide an apparatus in which the heating element extends through the still and in which part of the still rotates around said heating element in order that the oil by agitation may 10 be subjected to uniform heating; to provide an apparatus in which the vapor and residue lines are connected to stationary parts of the still so as to avoid difficulties with leakage through stuffing boxes or the like 15 and in general to provide an improved apparatus of the character referred to.

In the drawings:

Fig. 1 is a view partly in side elevation and partly in vertical section of the still 20 and certain of its connected parts. Fig. 2 is an enlarged view of the joint between the stationary and rotary parts of the still shown in Figure 1.

Fig. 3 is an enlarged sectional detail taken 25 on a line Y of Fig. 1.

Fig. 4 is a transverse sectional view taken on line A—A of Fig. 1.

Fig. 5 is an assembled view of the apparatus.

30 Referring to the drawings, 1 designates the still composed of a rotary portion 2 and stationary portion 3. The stationary portion 3 is supported by means of standard 4 while the rotary portion is mounted on standards 5 and 6. The abutting ends of the 35 still members 2 and 3 are secured by means of the joint 7, the arrangement being a double tongue and groove construction in which the member 8 rotates while the member 9 is stationary. The movable portion 2 of the still is provided with circumferentially 40 extending gears 10 and 11 which mesh with the small gears or pinions 12 and 13. The pinions 13 are rotated from driving 45 shaft 14 by means of the pulley 15 connected to any suitable source of motive power not shown. The still is heated by means of the longitudinally extending centrally disposed corrugated heating tube 16 50 which is heated by burner 17 and is provided with stack outlet 18. This member 16 at one end extends through part 3 of the still and at its other end is connected to the still by means of the tongue and groove joint 19.

This tongue and groove joint comprises the 55 stationary member 20 connected to the heating element and the movable element 21 connected to the rotating part of the still.

The oil is supplied to the still by means of the charging pump 22. The inlet side of 60 this pump is connected by pipe 23 controlled by valve 24 to any suitable source of supply while the discharge side of the pump is connected to the feed line 25 provided with throttle valve 26. The feed pipe 25 is connected to delivery pipe 27 which extends longitudinally through the still through the upper portion thereof and is provided at its lower side with a series of ports 28. The residue is drawn off from the stationary part 70 of the still through pipe 29 having throttle valve 30. The vapors pass out of the stationary part of the still through line 31 provided with throttle valve 32. The line 31 connects to dephlegmator 33 having baffles 34 75 and at its lower edge the angle partition member 35 and spaced cap 36. The reflux condensate, by means of the arrangement just described passes directly into the return pipe 37 leading to line 27. A valve 38 80 is interposed in line 37. Preferably the pipe 27 is of somewhat larger diameter than either the feed line 25 or reflux condensate line 37. The uncondensed vapors pass out of the dephlegmator through pipe 39 having 85 throttle valve 40 to the condenser coil 41. This condenser coil 41 is seated in water condenser box 42 and at its lower end is connected by pipe 43 to receiver 44. Receiver 44 is provided with liquid level gauge 45 and 90 pressure gauge 46. It also has gas outlet pipe 47 controlled by throttle valve 48 as well as liquid draw off pipe 49 controlled by throttle valve 50.

From the foregoing it will be seen that the 95 pipes entering the still and leaving the still are connected to the stationary part of the still thus simplifying the construction. Another feature of the invention which may be noted is the double tongue and groove 100 joint previously referred to and in the connection between the heating element and the still, a gasket 51 is preferably interposed in the joint.

We claim as our invention:

1. In an apparatus for treating oil, the combination with a still having a stationary portion and a movable portion, means for

- actuating said movable portion and a heating element taking the form of a longitudinally disposed tube extending through said portions, an oil feed passing through the stationary portion, and vapor and residuum outlets in said stationary portion.
2. In an apparatus for treating oil, the combination with a still having a stationary portion and a movable portion, means for actuating said movable portion and a heating element extending through said portions and stationary relative to the movable portion of the still, means for introducing oil to the still, and means for discharging vapors and residuum from the stationary portion.
3. In an apparatus for treating oil, the combination with a still comprising a stationary portion and a movable portion, a tongue and groove movable joint between said portions and means for actuating said movable portion and a heating element passing through said still.
4. In an apparatus for treating oil, the combination with a still comprising a stationary portion and a movable portion, a tongue and groove movable joint between said portions, means for actuating said movable portion, a heating element extending through said still portions and a movable tongue and groove joint connection between said heating element and said movable still portion.
5. In an apparatus for treating oil, the combination with a still having a movable portion and a stationary portion, means for actuating said movable portion and a vapor line, liquid draw off line and charging line connected to said stationary portion and a stationary central heating element passing through said still.
6. An apparatus for treating oil, comprising a still, the major portion of said still being rotatable with the minor portion at one end stationary, means for uniting the rotatable and stationary portions to form a fluid proof union therebetween, a heating conduit passing through the still, means for rotating the rotary portion of the still, an oil inlet carried by the stationary portion of the still, and residuum and vapor discharges also supported by said stationary still portion.

GUSTAV EGLOFF.
HARRY P. BENNER.
